STILT

Joseph Klimko, 3244 Powers Way,
Youngstown, Ohio 44502

Filed Dec. 7, 1967, Ser. No. 9,698

Term of patent 14 years

(Cl. D34—14)

The dominant features of my design reside in those portions shown in full lines.

I claim:

The ornamental design for a stilt, substantially as shown and described.
